UNITED STATES PATENT OFFICE.

DAVID P. MOORE AND SAMUEL B. PACK, OF WASHINGTON, DISTRICT OF COLUMBIA.

DESIGN FOR A CASING FOR PORTABLE SUCTION CLEANING-MACHINES.

40,748.

Specification for Design.

Patented June 28, 1910.

Application filed April 19, 1910. Serial No. 556,455. Term of patent 14 years.

To all whom it may concern:

Be it known that we, DAVID P. MOORE and SAMUEL B. PACK, citizens of the United States, residing at Washington, in the District of Columbia, have invented a new, original, and ornamental Design for a Casing for Portable Suction Cleaning-Machines, of which the following is a specification, reference being had to the accompanying drawings, forming part thereof.

In the said drawings:—Figure 1 is a

front perspective view of the casing, and Fig. 2 is a rear perspective view thereof.

We claim:—

The ornamental design for a casing for a portable suction cleaning machine, as shown.

DAVID P. MOORE.
SAMUEL B. PACK.
